Primary Examiner — Jasmine Mlinarcik(74) *Attorney, Agent, or Firm* — O'Banion & Ritchey LLP; John P. O'Banion(57) **CLAIM**

The ornamental design for a shield attachment for a headworn visor, as shown and described.

DESCRIPTION

FIG. 1 is a front perspective view of a shield attachment for a headworn visor showing my new design.

FIG. 2 is a front elevational view thereof.

FIG. 3 is a rear elevational view thereof.

FIG. 4 is a left side elevational view thereof, the right side being a mirror image.

FIG. 5 is a top plan view thereof; and,

FIG. 6 is a bottom view thereof.

The headwear outlined by broken lines in FIG. 1 depicts the environment of the shield attachment for a headworn visor and forms no part of the claimed design.
